UNITED STATES PATENT OFFICE.

FLORENCE BIRDSALL MILLER, OF SOUTH BEND, INDIANA.

SUSPENDER-WAIST.

1,299,204.

Specification of Letters Patent.

Patented Apr. 1, 1919.

Application filed January 20, 1919. Serial No. 272,138.

To all whom it may concern:

Be it known that I, FLORENCE B. MILLER, a citizen of the United States, residing at South Bend, in the county of St. Joseph and 5 State of Indiana, have invented certain new and useful Improvements in Suspender-Waists, of which the following is a specification.

This invention relates to an improvement 10 in suspender waists for children's use, and contemplates the provision of a waist of this character from which the nether garments may be suspended and supported, and which is so constructed as to be completely reversible, in that it has no fixed front or back 15 or inside or outside, considered in its application as a garment.

Children, particularly small children, in 20 the attempt to dress themselves, have difficulty in getting the undergarments, particularly the waist on correctly, and the help of an older person is usually required. An essential characteristic of the waist of the 25 present improvement, is that it is the same inside as outside and front and back, so that, as long as the child can place its head through the head opening of the waist, a wrong application of the waist cannot be made.

30 The invention in the preferred form of details will be described in the following specification, reference being had particularly to the accompanying drawings, in which:—

Figure 1 is a perspective view of the improved waist.

Fig. 2 is a side elevation of the same.

The improved suspender waist, as here shown, comprises what may be termed a body or shoulder portion 1, made up as a 40 narrow strip to fit over the shoulders and across the front and rear of the garment. This body portion 1 is formed with a neck opening 2, and at each side of said opening with depending side sections 3. Each side 45 section is formed with an arm-opening 4. The body portion 1 is, of course, shaped to fit over the shoulders, as at 5, while the front and rear parts of the side sections, as 6 and 7, are shaped to fit against the body of the 50 wearer. Those portions of the side sections below the arm openings, form tape-receiving 55 portions 8, and are of substantial width, though the side sections gradually decrease in width from the body portion 1.

55 Supporting tabs 9 and 10 are connected to

the front and rear of the body portion 1, preferably depending centrally between the side sections 3, and are preferably of the same width throughout. The tabs 9 and 10 depend from the body portion 1 spaced from 60 and wholly free of any connection with the side sections.

An important feature of the waist as thus formed, is that, so far as wearing it is concerned, it is fully and completely reversible, 65 the side sections being duplicates, and the front and back identical. Thus, so long as the child is able to put its head through the neck opening, and arms through the respective arm openings, the waist is in correct 70 position for use, whether in the position shown in Fig. 1, turned front to rear, or inside out, as compared with said shown position. This is a highly desirable characteristic for a child's garment of this nature, 75 as it is practically impossible for the garment to be put on wrong.

Both the tape receiving sections 8 and the tabs 9 and 10 are to be provided with means whereby the nether garments may be attached to and supported by the waist. On the sections 8, such supporting means comprises tapes, secured preferably on the longitudinal median line of the sections, and extending the full length of the sections and 80 slightly below the same. These tapes 11 are applied to both faces, that is inner and outer, of the sections 8, and each tape is provided with engaging means, here shown as buttons 12, there being preferably two buttons on 85 each tape. The button receiving portions of the tapes are preferably formed by looping or folding-over the tape and stitching same at the meeting points of the loop to provide short pendants, as clearly shown in Fig. 2. 90 The lower extended ends of the tapes are provided with means, here shown as eyelets 13, for connecting the usual hose supporters thereto.

The tabs 9 and 10 are also provided on 100 each face with tapes 14, extending from the upper edge of the body 1 to the ends thereof. The tapes are secured throughout their full lengths to the tabs, except at their lower ends, which are looped or folded-over to 105 provide two free pendants for the support of the buttons 15. By extending the tapes from the neck portion of the garment to the lower ends of the tabs and supporting the buttons thereon, the weight of the under- 110

garments is supported directly by the shoulder portions of the garment. Also each tab has duplicate securing means on each face thereof, as have the sections 8.

- 5 The duplication of the securing means on each face of each portion so provided, permits the use of the garment in any reversal of position, and the application of the nether garments to the waist even if one button is off. This is a material time saver to the busy mother, as otherwise the loss of the button, where but one is provided, would mean repair before the garment could be used.
- 10 15 The tabs 9 and 10 are wholly independent and separate from the side sections 3. This permits these parts to individually respond to strain or movement of the wearer without affecting other parts, and hence the bodily freedom of the user is increased. Furthermore, the parts noted, when independent as here constructed, may be readily spread apart in applying the garment, thus facilitating its use.
- 20 25 Owing to the particular construction of the garment and the fact that the body is not confined below the shoulder portion, it is apparent that the same may be easily applied, and that a garment of a given size 30 will readily fit different sized children to a substantially proper degree. This forms an additional feature of the present improvement, as it obviates the necessity of carrying a large variety of sizes by dealers handling the same, as well as providing for the growing child.
- 35 While the foregoing is the preferred form of my invention, I desire it to be understood that I do not limit myself to the precise 40 structure shown and described, as it is obvious that the same may be variously modi-

fied without departing from the spirit of the invention.

Having thus described the invention, what is claimed as new is:—

45 1. A reversible suspender waist having a shoulder portion, side sections depending therefrom, and supporting tabs depending from the shoulder portion between and wholly free of the side sections, the side sections being duplicates and the supporting tabs identical, and of like form in any reversal of position, and garment supporting means carried by both sides of the side sections and the tabs.

50 55 2. A reversible suspender waist having a shoulder portion, side sections formed with arm openings depending from the shoulder portion, and unbroken tabs depending from the shoulder portion between and wholly free of the side sections, said parts and the garment as a whole being of like form in any reversal of position, and garment supporting means carried by both sides of the side sections.

60 65 3. A reversible suspender waist having a shoulder portion, side sections depending therefrom, tabs depending from the shoulder portion between and wholly free of the side sections, and button supporting tapes 70 secured to both sides of the side sections and to the tabs.

75 4. A reversible suspender waist having a shoulder portion, side sections depending therefrom, tabs depending from the shoulder between and wholly free of the side sections, and tapes with supporting means secured to both faces of the side sections and to both faces of the tabs.

80 In testimony whereof I affix my signature.

FLORENCE BIRDSALL MILLER.
